UNITED STATES PATENT OFFICE.

FREELAND W. OSTROM, OF NEWARK, AND IRVING F. WEBB, OF ELIZABETH, NEW JERSEY, ASSIGNORS TO THE SINGER MANUFACTURING COMPANY, A CORPORATION OF NEW JERSEY.

FILLED-SACK-SEWING APPARATUS.

1,396,048.

Specification of Letters Patent.

Patented Nov. 8, 1921.

Application filed February 8, 1918. Serial No. 215,997.

To all whom it may concern:

Be it known that we, FREELAND W. OSTROM and IRVING F. WEBB, citizens of the United States, residing, respectively, at 5 Newark, in the county of Essex and State of New Jersey, and Elizabeth, in the county of Union and State of New Jersey, have invented certain new and useful Improvements in Filled-Sack-Sewing Apparatus, of 10 which the following is a specification, reference being had therein to the accompanying drawings.

This invention relates to improved means for closing the mouths of filled sacks by a 15 line of stitches and for conveying said sacks in an upright position under and past a sewing machine supported by the main frame of the sewing and conveying apparatus.

20 The invention has for an object to lessen the cost of construction and to effect increased production by the employment of an automatically controlled stitch-forming mechanism, provided with an emergency 25 mechanism, and automatically controlled means for holding in register the means for controlling the stitching operation with respect to the relative adjustments of the conveyer and the sewing machine.

30 The invention has for another object to provide a more conveniently operated apparatus better adapted to the requirements of machines of the present character.

In the accompanying drawings, which 35 form a part of the specification,

Figure 1 is a view in front side elevation of the present construction, the side guide-bar, conveyer-frame and carrier-belts being slightly broken away. Fig. 2 is a 40 plan view of the present construction with a portion of the carrier-belts and table-top broken away for a better understanding of the means employed for automatically controlling the seam formation. Fig. 3 is a 45 view in end elevation of Fig. 1. Fig. 4 is a view in elevation of the sewing machine belt-shifting and emergency mechanisms, as viewed in a direction opposite to that of Fig. 3, together with a portion of 50 the sewing machine. Figs. 5 and 6 are views, in detail, of the right and left-hand carrier brackets, respectively, the former being shown in section and the latter as a

plan view. Fig. 7 is a detail view of a portion of the conveyer motor bracket, 55 illustrating the manner of securing it to the conveyer-frame. Fig. 8 is a fragmentary view of one of the power-transmitting trip-bars for controlling the action of the stitch-forming mechanism and for suspending 60 such action. Fig. 9 is a detail view of certain of the elements employed for actuating the carrier-belts, referred to later. Figs. 10 and 11 are views in elevation of the means for automatically starting and 65 arresting the seam-forming operation, including the emergency mechanism. Figs. 12 and 13 are fragmentary views of the emergency mechanism. Fig. 14 is a view in elevation of the electric switch-box. 70

Referring to the drawings, the machine frame comprises the supporting standards or brackets 1 and 2 suitably secured upon the wooden base comprising the end pieces 3 and 4 and the tie-pieces 5, 6 and 7. Mounted upon said standards is the table 8 supporting the sewing machine bracket 9, having fixed to it the sewing machine head 10. Upon a bracket 11 supported by said table is suitably secured an electric motor 12, 80 controlled by the electric switch 12', said motor operating the sewing machine by means of the belt connection 13. As the stitch-forming elements herein employed are well known, it is not deemed necessary to 85 specifically refer to the same.

The conveyer-frame 14 is secured at nearly its opposite ends by screws, as 15, to the conveyer-frame brackets 16 and 17, secured by screws, as 18, to the sliding nuts 90 19 and 20, respectively, the tightening of the screws 18 effecting a sliding fit between the surfaces 21 and 22 of the nuts 19 and 20, respectively, with the surfaces 23 and 24 of the standards 1 and 2, and between 95 the surfaces 25 and 26 of said standards and the surfaces 27 and 28 of the brackets 16 and 17, respectively.

The electric-motor 29 has driving connections with the carrier-belts 30 and 31, independent of the driving connections of the motor 12 with the sewing machine and is suitably secured upon a bracket 32 carried by the conveyer-frame 14, said motor being controlled by a switch 33 located in the 100 105 switch-box 34.

Supported by the conveyer-frame 14 is a bracket 35, provided with shaft-bearings 36 and 37, and a bracket-lug 38. Journaled in said bearings is the friction-clutch driving shaft 39, upon which is mounted a loose pulley 40, carrying the cup-shaped disk 41, said pulley and disk being operatively connected by means of a belt 42 with the motor 29. A cone-shaped pulley 43 is suitably secured on the shaft 39 to rotate therewith and is movable longitudinally thereon. Upon the lug 38 is fulcrumed a clutch-controlling lever 44 acting, at the will of the operator and in opposition to the clutch-spring 45, to force said cone-disk into contact with the inner inclined surface of the disk 41 and effect power transmission from the motor 29 to the shaft 39.

A gear-shaft 46 is journaled in an upright position in bearings 47 and 48 formed on the bracket 35 and at its upper end carries a beveled gear 49 meshing with a like gear 50 carried by the shaft 39, said gear-shaft 46 carrying a worm-gear 51 meshing with a gear member 52, fast on the shaft 53, journaled in the bearing 51' and in suitable bearings formed in the frame 14. The shaft 53 carries the belt driving cylinder 54 provided with the rib 55 for directing the belts 30 and 31 in a given line of travel, a like cylinder 56, provided with a rib 55' being suitably journaled in the opposite end of the frame 14 and acting as an idler for the travel of said belts, which are supported between said cylinders by rollers, as 57, except as noted later.

A rock-shaft 58 is journaled in suitable bearings formed in brackets, as 59, secured upon the frame-base and to the forward end of said shaft is secured a bracket-arm 60, carrying an operating lever 61, provided with a contact member 62. To resiliently hold the operating mechanism in the position shown in Fig. 1 of the drawings, the rock-shaft 58 has secured thereupon an arm 63 and a spring 64, one end 65 of the latter bearing on the tie-piece 7 and its other end 66 being in contact with the arm 63, thereby forcing a stop-member 67, of the rock-shaft, into contact with the tie-piece 7. Secured upon the rock-shaft 58 is a crank-arm 68, linked at its free end to a chain connection 69 passing around an idler 69' and linked at its opposite end to an arm 70 projecting from a rocking standard 71, journaled at its opposite ends in bearing lugs, as 72, one of which is suitably secured to the under side of the table 8 and the other upon the tie-piece 5. The rocking standard carries a parallel bar 73 which, in practice, is adapted to act upon the lever 44 to move the clutch member 43 into engagement with the disk 41.

To adjust the conveyer-frame 14 to meet the requirements of sacks of various sizes, vertically arranged screw-rods 74 and 75 are threaded through the nuts 19 and 20,

respectively. The screw-rods are journaled near their upper ends in suitable bearings as 76, (one only of which is shown, see Fig. 3), carried by the standards 1 and 2, and carry at their upper ends gear-members, as 77 (one only of which is shown) meshing with like gear-members, as 78, upon crank-shafts, as 79, actuated by means of the crank-members 80 to effect the desired vertical adjustment of said conveyer-frame.

Referring now to the means employed for controlling the stitching operation, a belt-shifting bracket 81 is suitably secured to the sewing-machine bracket 9 and is provided with a lug 82. Upon the free end of the lug is pivotally mounted a belt-shifting lever 83, provided with belt-shifting fingers, as 84, a belt-shifting weight 85, a brake-member 85', and a flexible-connection supporting and directing element 86. The bracket 81 is provided with a flexible-connection directing element 87, and a flexible-connection supporting and directing element 88. The power-transmitting and arresting trip mechanism preferably comprises bars 89 and 89', having one of their ends, as 90, connected with a trip-bar crank-arm 91 of one of the roller-rods, as 92, capable of turning movement on pointed screws, as 93, secured against accidental movement by nuts, as 94. The other ends of the bars 89 and 89' are pivotally connected with a crank-arm 96 on the roller-rod 97, journaled in suitable bearings in the frame 14 and carrying at its inner end a flexible-connection actuating crank-arm 98, linked to one end of a flexible connection 99.

The flexible connection 99 passes over the element 86, under the element 87 and over the element 88, where its free movement is retarded by a bent spring 100, passing partly over the element 88 and carried by a flexible-connection adjusting lever 101 pivotally supported upon the bracket 81. The lever 101 is formed at one end with an apertured ear 102 for the passage of the flexible connection 99, to the depending end of which is attached a suspended weight 103 acting as a resistance member to the rocking movements of the crank-arm 98, which movements are limited in one direction by a stop-rod 104, on the roller-rod 97 and a stop-finger 105 projecting from the frame 14.

Attached to the other arm of the lever 101 is a chain 106 forming a flexible connection with the free end of a crank-arm 107, secured upon the rock-shaft 58.

When the sewing and conveying mechanisms are stationary, with no bag upon the trip-bars 89 and 89', the parts are substantially in the position shown, particularly in Figs. 1 and 3 of the drawings. In this position the operating lever 61 is held inclined to the right under the action of the spring 64, thereby causing the chain 106 to hold the long end of the lever 101 and con-

sequently the weight or resistance member 103 in raised position, which provides sufficient slack in the flexible connection 99 to permit the belt-shifting lever 83 to assume its stop-position under the action of the weight 85 and also to permit the trip-bars 89 and 89' under their own weight to assume their lowered position in the space 108 provided for the purpose.

10 In operation, the adjustment of the switches 12' and 33 starts the motors 12 and 29, respectively. The movement of the operating lever 61 to the left (see Fig. 1) actuates the rod 73, thereby moving the clutch-lever 44, producing frictional contact between the clutch-members 41 and 43, and driving the shaft 39, which by means of the gear connections described transmits motion to the carrier-belts 30 and 31. The actuation of the rock-shaft 58 at the same time moves the crank-arm 107 to produce slack in the chain 106, permitting the lever 101 and the resistance member 103 to drop into the full-line position shown in Fig. 10. 25 This movement takes up on the flexible connection 99, owing to the action of the spring 100 thereon, sufficiently to raise the trip-bars 89 and 89' into operative position, thereby rendering the automatic controlling means 30 for the stitch-forming mechanism potentially effective, but not sufficiently to lift the weighted end of the belt-shifting lever 83, owing to the greater inertia of the weight 85.

The carrier-belts 30 and 31 are now in 35 operation, but the sewing mechanism is still stationary. By placing a bag *b* upon the carrier-belts in substantially the position indicated in dotted lines in Fig. 2, the belts carry the same past the stitch-forming mechanism. In so doing, the bag contacts with and depresses the trip-bars 89 and 89', thereby actuating the crank-arm 98 to exert a pull on the flexible connection 99, pulling down the element 86 and consequently shifting the sewing machine driving belt from its loose to its tight pulley. The movement of the lever 83 at this time is due to the greater resistance of the weight 103. The shifting of the belt of course starts the sewing mechanism. After the bag is past the sewing mechanism and rides off the trip-bars 89 and 89', the weight 85 drops, disconnecting the driving means for the sewing mechanism, lifting the directing element 86 and consequently lifting the trip-bars 89 and 89'. From the foregoing description it is apparent that the trip-bars 89 and 89' and their connection with the belt-shifting lever 83 constitute automatic controlling means for determining the period of operation of the stitch-forming mechanism.

For the ordinary running of the machine, the emergency mechanism comprising the directing and frictioning elements for the 65 flexible connection 99 beyond the directing

member 86 could of course be dispensed with, this mechanism being only provided to meet the requirements of accidental conditions such as for instance the breaking of the needle or thread during the sewing operation, in which case it is desirable to stop the sewing mechanism at any point during the stitching of the mouth of the filled sack. In such emergency cases when it is necessary to release the operating lever 61 to stop the conveyer, before the stitching operation is completed, the sewing mechanism would continue in action, without the provision of an emergency stop mechanism. With the present device, in an emergency of the character referred to, when the operator releases the operating lever 61, the conveyer actuating mechanism is disconnected and the conveyer comes to rest. At the same time the rocking of the shaft 58 causes a downward pulling action upon the chain 106, thereby swinging the flexible-connection adjusting lever 101 on its pivot, causing the spring 100 to grip the flexible connection between it and the supporting and guiding element 88 and producing slack in the flexible connection 99. Inasmuch as the trip-bars 89 and 89' cannot take up this slack owing to their lowered position due to the weight of the bag upon them, this slack is taken up by the belt-shifting lever 83 under the action of the weight 85, thereby switching the sewing machine driving belt from the fast to the loose pulley and applying the brake 85' to stop the machine. When the machine is again started from this stopping position, the resistance member 103 drops downwardly owing to the slack produced in the chain 106 by the movement of the shaft 58, thereby taking up on the flexible connection 99 and consequently swinging the belt-shifting lever to starting position.

Having thus set forth the nature of the invention, what we claim herein is:—

1. In a filled sack sewing apparatus, in combination, sack-conveying mechanism, manually operated means for controlling the operation of said sack-conveying mechanism, stitch-forming mechanism, work-controlled means whereby said stitch-forming mechanism is automatically brought into and normally maintained in operation for a definite period during the operation of said sack-conveying mechanism, and an emergency mechanism adapted to be brought into action to arrest and restore the operation of said stitch-forming mechanism during the normal operation-period of the latter.

2. In a filled sack sewing apparatus, in combination, sack-conveying mechanism, manually operated means for controlling the operation of said sack-conveying mechanism, stitch-forming mechanism, work-actuated mechanism in inoperative position during the inaction of the sack-conveying mecha-

nism, and means brought into action by the starting of the sack-conveying mechanism to bring said work-actuated mechanism into effective position for determining the period of operation of the stitch-forming mechanism.

3. A filled-sack sewing apparatus comprising stitch-forming mechanism, sack-conveying mechanism, manually operated means for controlling the operation of said sack-conveying mechanism, automatic means for controlling the period of operation of said stitch-forming mechanism, and an emergency mechanism adapted to be brought into action to arrest and restore the effective action of said automatic controlling means.

4. A filled-sack sewing apparatus comprising stitch-forming mechanism, sack-conveying mechanism, manually operated means for controlling the operation of said sack-conveying mechanism, automatic means for controlling the operation of said stitch-forming mechanism, and an emergency mechanism adapted to arrest the effective action of said automatic controlling means.

5. In a filled-sack sewing apparatus, in combination, stitch-forming mechanism and sack-conveying mechanism, means for manually controlling the operation of said sack-conveying mechanism, means brought into action by the conveyance of a filled sack by said sack-conveying mechanism to control the operation of said stitch-forming mechanism and an emergency mechanism adapted to be brought into action by the controlling means for the conveying mechanism to stop said stitch-forming mechanism.

6. A filled sack sewing apparatus, comprising stitch-forming mechanism, sack-conveying mechanism, manually operated means for controlling the operation of said sack-conveying mechanism, automatic controlling means for determining the period of operation of said stitch-forming mechanism, an emergency mechanism adapted to be brought into action to arrest and restore the effective action of said automatic controlling means, and means permitting vertical adjustment of said sack-conveying mechanism.

50 7. A filled sack sewing apparatus, comprising stitch-forming mechanism, a sack-conveyer, automatic controlling means for determining the period of operation of said stitch-forming mechanism, means permitting relative vertical adjustment between said stitch-forming mechanism and said sack-conveyer, and an emergency stop-mechanism adapted to be brought into action to arrest and restore the effective action of said automatic controlling means and including a flexible connection one end only of which is connected with a member sustained by said sack-conveyer to provide for said vertical adjustment.

65 8. A filled sack sewing apparatus, com-

prising stitch-forming mechanism, a sack-conveyer, automatic controlling means for determining the period of operation of said stitch-forming mechanism, and an emergency stop mechanism for said stitch-forming mechanism adapted to arrest and restore the effective action of said automatic controlling means, said emergency stop-mechanism including an operating member sustained by said sack-conveyer, a resistance member, and a flexible connection between said operating member and said resistance member.

9. A filled sack sewing apparatus, comprising stitch-forming mechanism, a sack-conveyer, automatic controlling means for determining the period of operation of said stitch-forming mechanism, and an emergency stop-mechanism for said stitch-forming mechanism adapted to arrest the effective action of said automatic controlling means, said emergency stop mechanism including an operating member sustained by said sack-conveyer, a resistance member, a weighted belt-shifting member, and a flexible connection between said operating member and said resistance member.

10. In a filled sack sewing apparatus, in combination, stitch-forming mechanism, a sack-conveyer, means for vertically adjusting said sack-conveyer, and an emergency mechanism adapted to be brought into action to control the operation of the stitch-forming mechanism, said emergency mechanism including a resistance member self-adjustable in accordance with different adjusted positions of the sack-conveyer.

11. A filled-sack sewing apparatus comprising a sack-conveyer, an operating lever permitting manual control of the operation of said sack-conveyer, stitch-forming mechanism automatically operated by the conveyance of a filled sack by said sack-conveyer, and an emergency stop mechanism adapted to arrest and restore the operation of said stitch-forming mechanism by the movement of said operating lever to stop and start, respectively, the operation of said sack-conveyer.

12. In a filled-sack sewing apparatus, in combination, a sack-conveyer, stitch-forming mechanism and an emergency stop mechanism, manually operated means for starting and stopping the operation of said sack-conveyer, controlling means normally in inoperative position and adapted to be placed into operative position by the starting of said sack-conveyer for automatically determining the period of operation of said stitch-forming mechanism by the conveyance of a filled sack by said sack-conveyer, and a connection between said emergency stop mechanism and said controlling means whereby the operation of said stitch-forming mechanism is arrested and restored by the

actuation of said manually operated means to stop and start the operation of said sack-conveyer.

13. In a filled-sack sewing apparatus comprising stitch-forming mechanism, a sack-conveyer, a support for said sack-conveyer, automatic controlling means sustained by said support for determining the period of operation of said stitch-forming mechanism 10 and normally out of operative position, and means brought into action by the starting of said sack-conveyer for placing said automatic controlling means into operative position.
14. In a sewing machine, in combination, stitch-forming mechanism, a belt-shifting lever, means for normally holding said belt-shifting lever in position to render said stitch-forming mechanism inoperative, automatic controlling means including a flexible 20 connection for moving said belt-shifting lever to start said stitch-forming mechanism and determine its period of operation, and means including a suspended resistance member to arrest and restore the operation 25 of said stitch-forming mechanism while under the action of said controlling means.
15. In a sewing machine, in combination, stitch-forming mechanism, a belt-shifting

lever, means for normally holding said belt-shifting lever in position to render said stitch-forming mechanism inoperative, automatic controlling means including a flexible 20 connection for moving said belt-shifting lever to start said stitch-forming mechanism and determine its period of operation, and means including a suspended resistance member to arrest and restore the operation 25 of said stitch-forming mechanism while under the action of said controlling means.

In testimony whereof, we have signed our names to this specification.

FREELAND W. OSTROM.
IRVING F. WEBB.
